SHOE INSOLE WITH MOISTURE ABSORBING AGENT

Harold Miller, Bronx, and Anita Kiedish,
New York, N. Y.

Application August 6, 1949, Serial No. 108,884

3 Claims. (Cl. 36—3)

1

This invention relates to new and useful improvements in renewable insoles for footwear thereby to provide a readily applicable insert to be worn in and at the bottom of a shoe or the like; and, more particularly, the aim is to provide a novel and valuable such insole having therein a suitable moisture absorbing agent and an insole which at the same time is so constructed and has its component parts so arranged that, with some of said parts cushioning elements spacedly placed over the expanse of the insole, said elements (a) act as underlying resilient supports for all or the more important of the foot bones and joints, (b) function as partitional instrumentalities which establish a plurality of passages at the interior of the insole with a moisture absorbing agent positioned in one of the passages beneath an arched instep, and (c) provide passages adapted to act, in response to pressure from the foot, as suction exhibiting mediums for drawing moisture laden air from the feet toward and over the moisture absorbing agent.

The passages are provided in part by said cushioning elements, and in part by under surface portions of an upper sheet member included in the new insole, and in part by upper surface portions of a lower sheet member included in the new insole. These two members may be of any suitable strong and fairly flexible material. Preferably they are both inclusive of a single section of rubber sheeting, and with the lower one of said members preferably continuously and unbrokenly extended, that is, non-perforate; but with the upper one of said members perforated or equivalently foraminous at various points overlying the passages.

As the invention is further preferably carried out, said perforations are merely at locations at the fore part of the new insole, so that the perforations will be localized over the part of the insole to underlie the toes and the intertoe crevices all the way back to at least about the root portions of the toes, where, as is well-known, the perspiration from a foot, and sometimes highly offensively odorous perspiration, is chiefly exuded; and, in combination with this feature, the said upper member of the new insole is so made, over a length of the latter starting a little distance at the rear of the rearward limit of the perforated area, and extending all the way back to the heel portion of the new insole, as to constitute one type of two-ply structure. At the same time, the main rearward portion of said upper member, as the invention is further preferably carried out, while also so made as to con-

2

stitute a two-ply structure, provides another type of two-ply structure because inclusive of a lower ply of fairly stiff sheet metal, plastic or the like, this last-named ply fixed in position immediately below the top sheet component of the aforesaid upper sheet member; which top component is desirably a thin and tough textile fabric, as a woven one.

The aforesaid rubber sheeting included in the 10 upper sheet member is, in view of the inclusion on said sheet member of said metal or plastic lower ply thereof, of less length than the rubber sheeting constituting the aforesaid lower sheet member; which latter member extends unbrokenly over the entire length of the new insole.

Said fabric sheet, or equivalent, at suitably spaced points perimetral thereof, has tongue-like integral extensions for adhesive attachment to outer edge portions of said cushioning elements where the latter have their said edge portions at or substantially at locations marginal to the new insole.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top plan view showing a now favored embodiment of the invention; this view being partially broken away at the uppermost textile ply, and, within the limits of such break, also 35 partially broken away at the part of the ply immediately underlying said textile ply and, particularly, at said metal or plastic ply.

Fig. 2 is a side elevational view of Fig. 1.

Fig. 3 is an enlarged transverse vertical sectional view, taken substantially on the line 3—3 of Fig. 1.

Fig. 4 is an enlarged transverse vertical sectional view taken on the line 4—4 of Fig. 1.

Although the new insole need not necessarily be provided as rights and lefts, that is preferable; and the showings of the drawings may be taken, in regard to the illustrative embodiment of the new insole there shown, as indicative of an insole pursuant to the invention shaped for insertion in a shoe to be worn on the left foot.

Referring now to said drawings more in detail, and by reference numerals, the aforesaid cushioning elements, spacedly placed with special relation to the bones and bone-joints of the human foot, include in part a group of six of said ele-

ments, these all designated 10. It will be noted that said elements 10 are arranged roundingly of the heel and then extended forwardly for some distance along the outer side of the inner sole, to about the center of the shank region. Two other of said elements, these respectively marked 11 and 12, and both of rather large area, are placed as shown best in Fig. 1. Two further of said elements, and not so large as the elements 11 and 12, are located about as shown at 14 and 15. Two finally complementary of said elements, these respectively designated 16 and 17, are at the toe end of the insole.

These twelve cushioning elements, cut from say a sheet of sponge rubber of the thickness desired when uncompressed, are at any rate to be made of suitable softy resilient material.

Overlying the entirety of the top of the insole is the aforesaid topmost textile layer or ply, 18. For assisting in fixedly positioning all the cushioning elements in place, this ply 18 is cut so as integrally to have a plurality of tongue-like extensions 19, each for securement, as by a suitable adhesive, to a different one of the said cushioning elements, for instance in the manner shown in Fig. 3 in regard to the cushioning element 11.

In Fig. 1 a somewhat obliquely inclined line, at its central portion in full delineation and at its terminal portions in broken delineation, will be observed, crossing the insole generally laterally.

This line, traversing the cushioning elements 11 and 12, marks the rear limit of a ply 20 directly underlying the play 18; said ply 20 being the aforesaid rubber sheeting, and the same having the aforesaid perforations therethrough, said perforations being marked 21 and being shown as seven in number. With the said ply 20 held against facewise shift relative to the play 18, as by the aid of a coating of rubber cement or the like between these two plies, seven perforations through the play 18 are matchingly located relative to the perforations 21 as shown.

The line identified in the second preceding paragraph marks, also, the forward limit of the aforesaid thin metal or plastic secondary ply, the latter marked 22. By the use, here also, of a suitable adhesive in the form of a coating between the play 18 and said secondary ply 22, said plies 18 and 22 may be bonded against facewise shift of one relative to the other.

It should be appreciated, however, that the already mentioned securement of the tongue-like extensions 19 to the cushioning elements 10—17, plus other securements, all these conveniently effected by the aid of appropriate adhesives, all the parts are securely locked together against any relative movement other than those deliberately prevised as elastic compressions of said cushioning elements consequent upon walking by the wearer of the new insole or otherwise occurring movements of his foot-bones; among such parts being included the final complementary part, to wit, the bottoming ply, as aforesaid desirably of rubber sheeting, and designated 23.

The just mentioned "other securements," are adhesive bondings of the tops and bottoms of the cushioning elements to, respectively, the plies 20 and 22, and the play 23.

Thus, between the top and bottom sheet like structures of the new insole, and particularly between the cushioning elements 11—17, dependably permanently established passages 24 are provided. From Figs. 1 and 4 it will be noted that the thin metal or plastic secondary ply 22 is curved upward on the inner side of the insole be-

tween the adjacent edges of the elements 10 and 12 to form an arch support for the arch of the foot rested on the insole. There is a relatively large space between the adjacent edges of the elements 10 and 12 and a moisture absorbing member 30 is secured to the top face of the play 23 in the space between the elements 10 and 12. When the top plies are squeezed toward the bottom play 23 by a force applied to the top of the insole, the upward arched portion of the top plies will prevent moisture absorbing member 30 from being compressed under the weight. All of the passages between the plies 20 and 22 and the play 23 are in communication with the moisture absorbing member 30 and as pressures are alternately applied and relieved during walking, the action of the elements 10, 11, 12, 14, 15, 16 and 17 in being compressed and released will function as a pump to cause the moisture laden air within the shoe to be forced through the passages to contact the moisture absorbing member 30 and cause the air to be relieved of its moisture.

Said agent may be any suitable one, as for instance, such a composition as is specified in the now expired U. S. Patent No. 1,144,291, dated June 22, 1915. Such agent may be, for instance, in the form of a loose powder, or such powder, or a solution containing the same, has a constitution like that of blotter lint, raw cotton or the like.

From the foregoing, the marked advantages of the present concept, in attaining the objects hereinabove first recited, should be apparent.

While we have illustrated and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:

1. A laminated insole comprising a flexible one-piece bottom ply, a two-part upper ply spaced above said bottom ply a plurality of spaced cushioning elements mounted between the adjacent faces of said plies with their outer faces flush with the outer edges of said plies, said cushioning elements having their inner ends stopped short of the longitudinal center of said plies leaving passages between their adjacent sides and along the longitudinal center of said plies for the circulation of air and the insertion of a moisture absorbing agent, and a flexible covering ply secured in position over the top face of said upper ply, said covering ply in the areas of its periphery aligned with the outer faces of said cushioning elements having dependent tongue-like extensions secured to the outer faces of said cushioning elements.

2. A laminated insole comprising a flexible one-piece bottom ply, a two-part upper ply spaced above said bottom ply a plurality of spaced cushioning elements mounted between the adjacent faces of said plies with their outer faces flush with the outer edges of said plies, said cushioning elements having their inner ends stopped short of the longitudinal center of said plies leaving passages between their adjacent sides and along the longitudinal center of said plies for the circulation of air and the insertion of a moisture absorbing agent, and a flexible covering ply secured in position over the top face of said upper ply, said covering ply in the areas of its periphery aligned with the outer faces of said cushioning

elements having dependent tongue-like extensions secured to the outer faces of said cushioning elements, said upper ply being divided along a laterally extended line into a front piece of rubber sheeting and a rear thin metal piece.

3. A laminated insole comprising a flexible one-piece bottom ply, an upper ply spaced above said bottom ply, said upper ply being of multiple part formation, a plurality of spaced cushioning elements mounted between the adjacent faces of said plies and with their outer faces flush with the outer edges of said plies, said cushioning elements being of a lateral length less than one-half the width of said plies and positioned on opposite sides of the longitudinal center of said plies resulting in passages along the longitudinal center of said plies and between the adjacent sides of said cushioning elements for the circulation of air, and a covering ply secured to the top face of said upper ply and having dependent tongue-

5

like extensions at the areas of its periphery aligned with the outer faces of said cushioning elements which are dependent along and secured to the outer faces of said cushioning elements.
